UNITED STATES PATENT OFFICE

ROGER D. DE WOLF, OF ROCHESTER, NEW YORK

COMBUSTION CHAMBER AND DRAFT SYSTEM THEREFOR

Original application filed May 1, 1926, Serial No. 106,123. Divided and this application filed April 19, 1928. Serial No. 271,331.

This invention relates to combustion transversely across the combustion chamber, chambers for furnaces and the like, and has approximately on the line 5—5 of Fig. 3, for its principal object the provision of a generally improved combustion chamber which is more practical, efficient, and satisfactory than those heretofore known.

Another object of the invention is the provision of an improved draft system for combustion chambers, so that more satisfactory and efficient combustion of the fuel may be obtained at all times, even under widely varying loads.

A further object of the invention is the provision of improved means for preheating the air which is forced or drawn into the combustion chamber.

It is an additional object of the invention to provide a combustion chamber having an improved shape which allows room for expansion of the flame and of the products of combustion at the points where the need for such expansion is greatest, and which is so designed that the tendency of fused ash or slag to adhere to the walls of the combustion chamber is reduced to a minimum.

Still another object is the provision of a system of combustion and of a combustion chamber which are especially adapted for the efficient and satisfactory combustion of fuel in a pulverized or finely divided state.

To these and other ends the invention resides in certain improvements and combinations of parts, all as will be hereinafter more fully described, the novel features being pointed out in the claims at the end of the specification.

In the drawings:

Fig. 1 is a side elevation of a furnace illustrating one embodiment of the invention.

Fig. 2 is a front elevation thereof, with parts broken away, in order to show the structure better.

Fig. 3 is a vertical sectional view through one wall of the combustion chamber, taken approximately on the line 3—3 of Fig. 2.

Fig. 4 is a similar vertical sectional view, taken approximately on the line 4—4 of Fig. 2.

Fig. 5 is a vertical sectional view taken

approximately on the line 5—5 of Fig. 3. Fig. 6 is a plan of the upper part of the combustion chamber, with parts shown in section, the section being taken approximately on the line 6—6 of Fig. 8.

Fig. 7 is a vertical sectional view through part of the upper portion of the combustion chamber, the section being taken approximately on the line 7—7 of Fig. 8.

Fig. 8 is a vertical sectional view through part of the upper portion of the combustion chamber, the section being taken approximately on the line 8—8 of Fig. 6 and at right angles to the plane of Fig. 7.

Fig. 9 is an elevation of part of the front wall of the furnace, with the outer covering removed and with parts broken away.

Fig. 10 is a horizontal section of the same portion of wall shown in Fig. 9.

Fig. 11 is a vertical sectional view through part of one of the walls of the combustion chamber, illustrating certain details of construction; and

Fig. 12 is a perspective view of a part of the front wall of the combustion chamber, illustrating certain details.

The same reference characters refer to the same parts throughout the several views.

The furnace shown in this application is especially adapted for burning fuel in pulverized or finely divided form, but it should be understood that many of the features are applicable equally well to other types of furnaces for burning other kinds of fuel.

This application is a division of my application, Serial No. 106,123, filed May 1, 1926, Patent No. 1,810,203, for furnaces and the like.

In the embodiment illustrated in the drawings, there is shown a furnace having a combustion chamber indicated generally by the numeral 21, this combustion chamber being substantially rectangular and having an outlet at the upper portion of its rear side.

A boiler enclosing structure, indicated generally by the numeral 22, is built partly on top of and partially at one side of the combustion chamber, as shown in Fig. 1, and receives the products of combustion, which

pass out of the combustion chamber. Suitable water tubes or other boiler elements, indicated diagrammatically by dotted lines in Fig. 1, are placed within the boiler enclosing casing 22 so that they absorb the heat resulting from combustion. A suitable duct 23 is connected to the structure 22 to remove the products of combustion therefrom, and this duct preferably is connected to a stack or other appliance for creating a draft in the furnace.

The walls of the combustion chamber and of the boiler enclosing structure may be constructed in any suitable manner. In the embodiment here shown, the combustion chamber is of considerable height, and the form of wall construction used is especially adapted to combustion chambers of such form. The wall construction is shown in detail in the parent case of which this application is a division, and it will, therefore, be described only briefly in this application, reference being had to the parent case for a more complete description of the details.

In a furnace structure of considerable height, the weight of the upper portion of the structure often bears excessively on the lower part thereof. Furthermore, if the lower portions of the walls have to be renewed for any reason, it is usually necessary to tear down the whole wall, as there is nothing to support the upper portion of the wall when the lower part is removed. To eliminate these undesirable features, there has been provided in the present instance a skeleton or framework upon which the walls are supported at intervals. This skeleton not only bears the weight of the upper part of the walls, so as to reduce the weight on the lower portion, but also acts as supporting means for the upper portion even when the lower part is entirely removed for repairs or replacement.

This framework or skeleton comprises upright beams 25 spaced at intervals along the outline of the walls of the furnace, and provided with suitable braces and anchoring means. Angle bars 26, best shown in Fig. 12, are fixed horizontally to the upright beams 25 so that they provide a series of vertically spaced flanges extending inwardly from the beams 25 toward the center of the furnace. The horizontal flanges formed by these angle bars 26 constitute supporting ledges on which the walls of the furnace are supported at vertical intervals. Each section of wall supported on one flange is independent of the sections above and below it, so that it neither bears against the section below nor carries the weight of the section above. On each of the flanges 26 and opposite each of the beams 25 there is mounted a hanger block 27 which is clamped securely to the adjacent beam 25 by clamping members 28 best shown in Figs. 10 and 11. These hanger blocks 27

are formed with cut-out portions 29 and wing portions 30, as illustrated clearly in Fig. 12.

On top of each hanger block 27 there is built up a column of similar hanger blocks 31, these latter blocks having similar cut-out portions 29 and wings 30, but being slightly shorter than the blocks 27 so that the lowermost block 27 which rests on the shelf 26 projects slightly further inward than the column blocks 31 which are superimposed on it. This is shown clearly in Figs. 10, 11 and 12. Each of the blocks 31 in the column is secured to the adjacent beam 25 by clamps 28, and the column of hanger blocks extends upwardly from one flange 26 to a point just beneath the next higher flange, as illustrated in Fig. 11.

The lining of the combustion chamber or other parts of the furnace may comprise heat resisting elements such as the fire bricks 35. It will be noted from Figs. 10 and 12 that each brick has an end interlocked with one of the hanger blocks 27 or 31, the brick having its ends so shaped that it will engage in the cut-out portion 29 behind the wing 30 of the hanger block. Thus each brick is kept in place and prevented from falling out of the wall. Each brick also has a portion extending across the face of the hanger block to approximately the center line thereof, as shown in Figs. 10 and 12 so that it meets a similar extension on the corresponding brick on the other side of the same hanger block and thus completely protects the hanger block from heat by covering the entire face thereof.

The lining bricks 35 which cooperate with the long hanger blocks 27 are made narrower than the other bricks which cooperate with the shorter blocks 31, so that the inner surface of the finished wall is smooth, as shown in Fig. 11. The brick next above each of the long hanger blocks 27 rests upon the ledge formed by the inwardly projecting end of the hanger block, and thus the lining bricks are divided into independently supported vertical columns resting upon the long hanger blocks 27 which, in turn, are supported by the ledges 26. The narrow lining bricks which are placed opposite the long hanger blocks rest upon and form part of the column of bricks immediately below those long hanger blocks, as shown clearly in Fig. 11. In order to allow for expansion, cracks 37 are left between each column of hanger blocks and lining bricks and the next column above it. These cracks are preferably filled with some heat resisting compressible packing, for example flaked asbestos.

It will now be seen that the walls are divided into independently supported vertical units carried by the angle bars 26 attached to the upright beams 25. If repairs to the wall are needed at any point, a limited sec-

tion of the wall may be torn down without affecting the sections above it. Thus an efficient form of construction is provided, in which the cost of repairs and the time consumed thereby are reduced greatly. Also, a wall construction in this form may be carried to any desired height, since the weight is supported by the beams 25 and does not cause undue crushing strain in the lower parts of the wall.

Preferably the side walls of the combustion chamber, at least in the lower portion thereof, are flared outwardly so that the combustion chamber has a downwardly increasing cross section, as shown in Figs. 2 and 5. When the walls are formed in this manner, there is less tendency for clinker to adhere to the walls, since the liquid drops of fused ash or other products of combustion will have a tendency to drop off of the walls into the ash pan 40 rather than to run down the sides of the walls and solidify thereon. This flared formation of the walls of the combustion chamber is also useful for another purpose. As will be explained in greater detail below, the fuel is preferably admitted to the top of the combustion chamber, and the flame travels downwardly to a point near the bottom of the chamber, then turns and ascends again. The greatest cross sectional area is needed at or near the point where the flame turns, and it is just at this point that the increased area is provided in the present construction. Also, by increasing the cross section of the combustion chamber in the downward direction of flame travel, additional space is provided where it is most needed for the expansion of the products of combustion.

The top wall of the combustion chamber may be formed in any suitable manner. For instance, as shown in Figs. 3, 4 and 5, beams 45 may extend across the top of the combustion chamber and hanger blocks 46 may be secured thereto, by clamps 47, fire bricks 48 being supported from and held in place by the hanger blocks 46.

As has been mentioned before, this combustion chamber is especially adapted for burning pulverized or finely divided fuel, although it may be used with fuel of other kinds or forms. There is shown in the present instance a pulverizer 50 adapted to receive coal by gravity through a chute 51. A separator 52 may be provided at the outlet of the pulverizer for separating the coarser particles from the finer ones and for returning the former to the pulverizer. A blower 53 draws the pulverized fuel up from the pulverizer 50 through the separator 52 and delivers it through a conduit 54 to the fuel inlet 55. As shown in Fig. 6, a plurality of fuel inlets may be formed in the combustion chamber, and a separate pulverizer and blow-

er may be used for each fuel inlet if desired, or a single pulverizer and blower may be used for two or more of the inlets. The fuel inlets in the present instance are shown as extending through the top of the combustion chamber, but other suitable positions might be used if deemed preferable.

The fuel, after entering the combustion chamber through one or more of the inlets 55, will pass downwardly through the combustion chamber, burning as it travels. At a point near the bottom of the chamber, the flame will turn and pass upwardly again and into the boiler enclosing structure 22 and thence to the stack. If desired, suitable air or water preheaters may be provided in the connections to the stack or elsewhere, and suitable forced draft mechanism may be employed.

In order to promote complete and efficient combustion of the fuel, it is desirable to admit air into the combustion chamber in addition to such air as may be admitted along with the fuel, and it is also desirable to be able to control the air supply to adapt it to varying conditions. The means for doing these things will now be described.

Covering members 60, best shown in Figs. 10, 11 and 12, may be fixed to the outer edges of the upright wall beams 25. Thus, the walls of the combustion chamber are, in effect, made hollow, and are provided with a series of substantially vertically extending conduits or ducts. The covering member 60 forms one of the sides of each of these ducts, the lining members 35 form another side, while the beams 25 and hanger blocks 27 and 31 serve as partitions to separate each conduit from the adjacent conduits at either side.

The conduits in the front wall of the combustion chamber may be divided into upper and lower portions by baffle walls 61, as shown in Figs. 3 and 4, while the conduits in the side walls may extend throughout the full height of the combustion chamber. It should be understood that the terms "front" and "side" are used simply for ease of description, and are not to be taken in a limiting sense. The upper conduits in the front wall, above the baffle walls 61, may be designated by the numeral 62, while the lower conduits in the front wall are marked 63. The conduits in the side walls are denoted 64.

Openings 65 may be formed in the front wall of the combustion chamber leading from each of the conduits 62 into the chamber, each of the conduits having a series of these openings vertically spaced from one another, as shown especially in Figs. 3, 4 and 5.

In order to prevent direct radiation of heat through the openings 65, baffle plates 72 may be placed opposite each of the openings, within the channels 62 and slightly spaced from

outer surfaces of the lining bricks 35, as shown in Figs. 3, 4 and 12. These baffle members 72 may rest against flanges 73 formed on the hanger blocks 27 and 31, and may be held in place against these flanges by vertical bars 74 (Fig. 9) which extend over several of the baffle plates 72 and hold them in place, these bars 74 being held inwardly against the baffle plates by cross bars 75 which have their ends set against the clamping devices 28, as shown in Figs. 9 and 10. Posts 76 hold the baffle plates 72 vertically spaced from each other, so that each plate will be properly placed in alinement with one of the openings 65, as shown in Figs. 3, 4 and 9. These baffle plates 72 therefore prevent heat from radiating directly out through the openings 65 against the cover member 60 to such an extent as to injure this covering, but they do not interfere with the passage of air from the conduits 62 through the openings 65, for the air may flow around the edges of these baffle plates as indicated by the arrows in Figs. 3 and 4.

25 A part of the conduits 64 in the side walls of the combustion chamber are connected at their upper ends through openings 66a to a conduit 66 which extends around the sides and the front of the combustion chamber, and is connected through an opening 66b to the upper ends of the conduits 62 in the front wall. The openings 66b from the conduit 66 into the conduits 62 is preferably controlled by a plurality of dampers 67 (Figs. 3 and 4) 30 having operating members 68 so that the dampers may be opened or closed, as desired, either individually or in gangs. The conduits 64 in the side walls have inlet openings 69 at their lower ends, these openings being 35 controlled by dampers 70 which may be provided with suitable operating means.

If the dampers 67 and 70 be opened, it will be seen that air may enter the conduits 64 at their lower ends and pass upwardly therein, in the direction of the arrows in Fig. 5. As the air passes upwardly through these conduits, it becomes heated by contact with the hot lining walls of the combustion chamber and serves at the same time to absorb heat 40 from the walls and to cool them considerably. Thus the effective life of the furnace lining is lengthened, because the bricks, when kept cool by means such as this, do not burn out as rapidly as when no cooling means is provided.

45 The heated air rising through the conduits 64 passes through the openings 66a is collected by the conduit 66 and carried around the sides of the combustion chamber to the front, as shown especially in Figs. 6 and 7, where it passes through the openings 66b into the upper ends of the conduits 62. The air then flows down these conduits and through the openings 65 into the combustion chamber, in 50 proximity to the burning fuel therein. This

provides some of the additional air necessary to obtain proper combustion of the fuel.

When the furnace is being operated at a low rate, some of the dampers 67 and 70 may be fully or partially closed, so that the supply of air flowing into the upper ends of the conduits 62 is limited. It should be noted that the air in these conduits flows in substantially the same direction as the travel of the flame within the combustion chamber, and comes first to those openings 65 which are nearer to the fuel inlet. In order to reach the lower openings 65 which are farther from the fuel inlet, the air must flow through a greater length of the conduits 62, which will, of course, produce greater frictional resistance to the flow. Thus the air tends to flow into the combustion chamber through the upper openings 65, since this is the path of least resistance, rather than to continue along the conduits and enter the combustion chamber through openings nearer to the bottom thereof. In this way, practically all of the air flowing in the conduits 62 when the furnace is operating at a low rate will enter the combustion chamber through openings 65 comparatively near the fuel inlet, where it is most needed for efficient combustion, and very little air will find its way through the lower openings 65.

When the furnace is being operated at a high rate, however, a greater quantity of air is admitted to the conduits 62, and an increased amount of fuel is introduced into the combustion chamber. Under these conditions, it would be undesirable to have the air distributed in the same proportions mentioned above, for if most of the air in the conduits 62 passed through the upper openings 65, it would have too great a cooling effect upon the burning fuel. At high load, therefore, a greater proportion of the air should pass by the upper openings 65 and should continue along the conduits 62 so as to enter the combustion chamber through some 100 of the openings 65 farther down.

This desirable result is accomplished largely automatically by the present construction. When large quantities of air are flowing through the conduits 62, it is obvious that the greater part of the air is no longer able to pass through the openings 65 near the upper ends of the conduits, for the resistance to the flow of such a large amount of air through these openings is too great. Consequently 105 a large part of the air flows on down the conduits 62 and passes through other openings 65 farther away from the fuel inlet. Furthermore, when the furnace is being operated at a higher rate, the so-called "chimney effect" 110 is more pronounced, and will produce a greater draft in the lower part of the combustion chamber than in the upper part thereof. This will tend to draw a greater quantity of air through the openings 65 in the lower 115

portions of the conduits 62 than through the openings in the upper portions. In this way the air is distributed differently when the furnace is operating at different rates or under different loads. The distribution, as above pointed out, is largely automatic, and the present construction is very effective in promoting efficient combustion at all times in furnaces which must be operated at different rates from time to time.

The conduits 63 in the lower portion of the front wall of the combustion chamber may be provided with inlet openings 80 at their lower ends, these openings having dampers 81 controlled by operating members 82. A part of these conduits (for example, each alternate conduit) may have vertically spaced openings 83 extending through the wall of the furnace into the combustion chamber, as shown in Fig. 4, these openings 83 having baffle plates 72 similar to those associated with the openings 65.

These conduits 63 which open into the combustion chamber at 83 thus form additional means for admitting air into the combustion chamber in proximity to the path of flame travel. The air entering the conduits 63 through the inlets 80 and rising through the conduits becomes preheated by contact with the lining walls of the combustion chamber and serves to keep these walls cool, as is the case also with the air in conduits 62 and 64. Thus the conduits 63 having the openings 83 form a means for admitting preheated air to the lower part of the combustion chamber in proximity to the path of flame travel, and also a means for cooling the walls of this part of the combustion chamber. When the furnace is operating at a low rate, the dampers 80 may be placed so that little or no air enters the lower part of the combustion chamber through the openings 83. When the rate is increased, the greater volume of air required may be admitted partly by allowing air to enter the openings 83 and partly by allowing an increased quantity of air to enter the combustion chamber by way of the conduits 62 and openings 65.

The remaining conduits 63 which do not have openings 83 formed therein, are provided at their upper ends with openings 84 leading into a duct or conduit 85 which extends across the front of the combustion chamber, as shown in Figs. 1 to 4. These conduits 63 which open into the duct 85 are provided with inlets 80 and dampers 81, similar to those provided for the conduits having the openings 83 leading into the combustion chamber. The duct 85 is connected by a conduit 86 to the pulverizer 50, as shown in Fig. 1. Thus the air passing through part of the conduits 63, and becoming preheated therein, is collected in the duct 85 and conducted to the pulverizer, where it is mixed

with the fuel prior to the injection thereof into the combustion chamber.

It was mentioned above that part of the conduits 64 in the side walls of the combustion chamber were connected by means of the conduit 66 to the upper ends of the conduits 62 in the front wall of the furnace. The remaining conduits 64 in the side walls which are not so connected to the conduits 62 may open into a duct 90, best shown in Figs. 6 and 7, this duct 90 having branches 91 leading to air inlet openings 92 adjacent and preferably surrounding the fuel inlet openings 55. Those conduits 64 which are thus connected to the inlets 92 have air inlet openings 69 and dampers 70 at their lower ends, similar to the inlets and dampers provided for the rest of the conduits 64.

The inlet openings 92 provide means for injecting air into the combustion chamber closely adjacent to the fuel inlet, this being a point at which air is needed and in which it will be of considerable benefit in promoting efficient combustion.

It will now be seen that an improved combustion chamber has been provided, which is equipped with means for cooling the walls thereof, this cooling means serving also as air preheating means. Part of the air thus preheated is mixed with the fuel before its injection into the combustion chamber; another part is injected into the combustion chamber adjacent the fuel inlet; and other parts of the preheated air are arranged to enter the combustion chamber through openings spaced in the direction of fuel and flame travel and in proximity to the line of travel thereof. A portion of this last mentioned quantity of air is conducted through passageways so arranged that it tends to enter the combustion chamber at points comparatively close to the fuel inlet, and encounters increasing resistance as it passes these points to enter the combustion chamber farther along the path of travel of the flame. Various dampers are arranged for controlling the quantity of air admitted to each part of the combustion chamber. Thus a highly satisfactory and efficient draft system is disclosed, which has many advantageous and desirable features.

Although the term "furnace" has been used throughout this specification, it should be understood that this combustion chamber has been described in connection with a furnace only by way of example, and is not limited in its application to boilers or furnaces of any particular type, but may be used wherever any sort of combustion chamber is desired.

While one embodiment of the invention has been disclosed, it is to be understood that the inventive idea may be carried out in a number of ways. This application is therefore not to be limited to the precise details shown, but is intended to cover all variations and modifica-

tions thereof falling within the spirit of the invention or the scope of the appended claims

I claim as my invention:

1. In a furnace construction, the combination with a combustion chamber, of means for admitting fuel thereto, a plurality of separate conduits extending substantially vertically in a wall of said combustion chamber, said wall having a plurality of spaced openings leading from the lower portion of one conduit into said combustion chamber, and a plurality of spaced openings leading from the upper portion of another conduit into said combustion chamber, means for admitting air to the upper end of the conduit having openings in its lower portion, and means for admitting air to the lower end of the conduit having openings in its upper portion.

2. In a furnace construction, the combination with a combustion chamber, of means for injecting pulverized fuel into the top of said chamber, a plurality of substantially vertical conduits in the front wall and side walls of said combustion chamber, said conduits having inlet openings leading from the conduits in the front wall into said combustion chamber, means for admitting air to the lower ends of the conduits in the side walls, means for connecting the upper ends of a part of the conduits in the side walls to the upper ends of the conduits in the front wall, and means for collecting air from other conduits in the side walls and introducing it into the top of the combustion chamber adjacent the inlet for said pulverized fuel.

3. In a furnace construction, the combination with a combustion chamber, of means for injecting pulverized fuel into the top of said chamber, a plurality of substantially vertical conduits in the front wall and side walls of said combustion chamber, said conduits having inlet openings leading from part of the conduits in the front wall into said combustion chamber, means for admitting air to the lower ends of the conduits in the side walls, means for connecting the upper ends of a part of the conduits in the side walls to the upper ends of a part of the conduits in the front wall, means for admitting air to the lower ends of the rest of the conduits in the front wall, means for collecting air from the upper ends of a part of said last named conduits, and means for mixing said collected air with the pulverized fuel prior to its injection into the combustion chamber.

4. In a furnace construction, the combination with a substantially vertically arranged combustion chamber, of a plurality of conduits in the front and side walls of said combustion chamber, mechanism for pulverizing fuel, means for leading pulverized fuel from said mechanism and injecting it into said chamber, means for admitting air to the lower ends of said conduits in a side wall of the chamber, means for collecting air from

the upper ends of certain of said conduits having admitting means in their lower ends and for admitting such collected air into said combustion chamber in proximity to the fuel inlet, means for collecting air from the upper ends of certain other of said conduits having admitting means in their lower ends and for supplying such collected air to the upper ends of certain of the conduits in the front wall, such front wall conduits having inlets leading into said chamber, means for admitting air to certain other conduits in the front wall, and means for collecting air from said last named conduits and for mixing such air with the pulverized fuel prior to its injection into said chamber.
